UNITED STATES PATENT OFFICE.

ISAAC T. MONTROSS, OF PEEKSKILL, NEW YORK.

DESIGN FOR A STOVE.

SPECIFICATION forming part of Design No. 12,849, dated April 4, 1882.

Application filed February 13, 1882. Term of patent 7 years.

To all whom it may concern:

Be it known that I, ISAAC T. MONTROSS, a citizen of the United States, residing at Peekskill, in the county of Westchester and State 5 of New York, have invented and produced a new and original Design for a Stove, of which the following is a specification.

The nature of this invention relates to a design for stoves; and it consists in the ornamental configurations hereinafter described and claimed, and illustrated in the drawing, which shows in perspective a stove ornamented in accordance with my design.

The letter A indicates the upper oven-door, 15 upon which is formed in relief the name-plate B, resembling in outline a rectangle cut away at one corner, thereby producing a novel and attractive figure. The face of this plate is surrounded by a plain raised border, a, that is interrupted by a scroll, a', on one of the five sides of the figure. Alongside of this scroll a small space, a'', is surrounded by a border, a'', produced by two beads crossed at one end, and at their other ends uniting with the scroll. Upon 25 the oven-door, and running around a portion of the base of the raised plate B, is a chain, a'', formed in relief. The name-plate is located in one corner of a space, b, that is inclosed by an ornamental rectangular border. Two sides 30 of this border are composed of bars b', while the remaining sides are composed in part of the chain a'' and in part of bars b''. In this figure or rectangular border, formed by said bars and chain, I form at corners diagonally 35 opposite each other the scrolls b' and b'', that are respectively intersected by darts or arrows b' b''. The entire configuration formed by the space b and its border, composed of bars, scrolls, and a chain, is raised, and around the margin 40 of the door is a plain molding, b''. The space b is further ornamented by two configurations, one consisting of a chain, C, arranged across the lower portion of said space and composed of alternate large and small circular links 45 formed by a bead that is convolved so as to form the links. The remaining ornamental figure in relief on space b partially fills the ground not occupied by the name-plate and the chain last described. This figure consists 50 of a scroll, C'', intersected by two crossed darts or arrows, and having a branch running up to-

ward the top of the space, a small arrow, C'', being pendent from the upper portion of this branch.

Upon a horizontal molding, C', extending 55 partially around the middle of the stove, is formed in relief a chain, D, composed of alternate large and small circular links. This chain is formed by continuous beads intertwined to form the links in the same way as the chain 60 C, hereinbefore described.

Upon a horizontal molding, C', extending 65 partially around the middle of the stove, is formed in relief a chain, D, composed of alternate large and small circular links. This chain is formed by continuous beads intertwined to form the links in the same way as the chain 70 C, hereinbefore described.

The face of the lower oven-door, D', is ornamented by a marginal molding, e, and a central rectangular-shaped figure in relief. This figure partakes in its general character of the 75 rectangular border shown upon the upper door. It consists of a space, E'', surrounded by a rectangular border composed of vertical and horizontal bars or beads, f, and a chain, f', around one corner of said border. At two 80 corners, diagonally opposite to each other, are scrolls g g, with intersecting darts or arrows, respectively similar to the scrolls b' b'' upon the upper oven-door. Within the space surrounded by this border is a chain, e'', similar 85 to the chain C, already described.

The side fire-door G is ornamented like the lower oven-door, with the exception that the chain e'' shown on said oven-door is omitted.

The side door, H, opening just above the 80 grate, is ornamented similarly to the fire-door G, and the lower side door, I, opening below the grate, is ornamented similarly to either of the two doors above it.

The extension top or shelf K at the back top 85 portion of the stove is formed with a transverse line of circular openings, L, and a series of parallel slots, l, terminating at each end near a small circular opening. These slots are alternately of unequal length, some of them being in the line running between the large circular openings L and others stopping short of the said openings. This construction forms ornamental open-work, composed of bars and circular openings, as shown. 90

The shelf N at the end of the stove is formed and ornamented in a similar manner to the rear extension-shelf, K, and hence does not require description. 95

Below the end shelf is a panel, O, bearing 100 a rectangular figure similar to the fire-door I, and at the upper front portion of the stove is

a draft-door, P, bearing an ornamental rectangular figure, also formed like that upon said fire-door.

At the four lower corners of the stove are 5 scrolls Q, in relief, two at each corner. These scrolls each form two oval-shaped figures, the upper one of which tapers to a point comprising scroll-work.

The chain D runs around the stove, commencing at a point to one side of the door H, 10 and, passing under the shelf N, terminates at a point adjacent to the other side of said door and continues around the range.

The lower corners of the range are 15 ornamented by short chains R, composed of large and small links, similar in outline to the ornamental chain D.

The front damper-door, P², may be 20 ornamented in a manner similar to the fire-door already described.

What I claim as my design, and desire to secure by Letters Patent, is—

1. In a design for a stove, the name plate formed in relief upon the oven-door, and having the configuration of a rectangle with one corner cut away, substantially as shown.

2. In a design for a stove, the five-sided name-plate formed in relief upon the stove-door, and having the border a interrupted by 30 a scroll, substantially as shown.

3. In a design for a stove, the five-sided raised name-plate located upon the stove-door, the border a for said name-plate, interrupted at one point by a scroll, and the space a², bordered by two bars, a², crossing at one end, and at 35 their remaining ends uniting with said scroll, substantially as described.

4. In a design for a stove, the raised five-sided name-plate located upon the stove-door 40 and partially surrounded by a chain, substantially as shown.

5. In a design for a stove, the oven-door, having a space inclosed by a rectangular border composed of the four bars, with the chain

a² at one corner and two scrolls at corners diagonally opposite each other, and the name-plate located within said space, substantially as shown.

6. In a design for a stove, the oven-door, having a space inclosed by an ornamental border, with the name-plate and a chain located within said space.

7. In a design for a stove, the oven-door, having a space inclosed by an ornamental border, with the name-plate, chain C, and the scroll C² located within said space, substantially as shown.

8. In a design for a stove, the oven-door, having a space inclosed by a rectangular border consisting of four bars, with a chain around 60 one corner, and two scrolls at diagonally-opposite corners, with a chain located within the said space and composed of alternately large and small links formed by a bead convolved to form the said links.

9. In a design for a stove, the chain D, extending around the middle portion of the stove, and composed of alternately large and small links, substantially as shown.

10. In a design for a stove, the chains R at 70 the lower corners of the stove, and composed of large and small links, substantially as shown and described.

11. In a design for a stove, the scrolls Q at the four lower corners of the stove, as shown.

12. In a design for a stove, the shelf formed with a transverse series of circular openings, and with a longitudinal series of slots, terminating near small openings at their ends, substantially as described.

In testimony whereof I have hereunto set my hand in the presence of two subscribing witnesses.

ISAAC T. MONTROSS.
